UNITED STATES PATENT OFFICE.

THOMAS J. SULLIVAN, TUSCALOOSA, ALABAMA.

GOVERNOR FOR CARBIDE GAS GENERATORS.

Application filed November 10, 1926. Serial No. 147,454.

This invention relates to a governor for carbide gas generators, and particularly to a construction for controlling the feed of carbide to the generator dependent upon the pressure of gas therein.

Previous constructions of motor and governor for such carbide feed have involved more or less complicated trains of gears or clock work adapted to be retained and released by means controlled by the gas pressure, and such devices materially increase the cost of production of the generator while providing a mechanism requiring frequent attention and repairs. To avoid these objections my invention provides a simple driving drum adapted to be clutched to a crank shaft actuating the carbide feed, and controlling the operation of said shaft by a cylinder and piston governor having a valved by-pass opened and closed relative to the gas pressure within the generator. Such a structure obviates the use of all gearing and provides for the direct driving of the feed shaft from the drum and a governor connection from said shaft freely operable when the gas pressure is below the maximum and adapted to be graduated in operation dependent upon such pressure. By the provision of the by-pass connection having a pressure control valve the speed of operation of the feed is determined while the piston is held against movement when the required pressure of gas is reached so that the operation of the feed is discontinued but left free for resumption upon a reduction of pressure which would permit operation of the piston within the cylinder.

The invention has for an object to provide a novel and improved construction including a generator having a feed shaft and a driving drum connected to said shaft together with a cylinder and piston governor connected to said shaft and formed with a by-pass having a valve controlled by the gas pressure of the generator.

Another object of the invention is to provide an improved construction by which the feed shaft is provided with a crank arm having a pitman extending therefrom to a cross head, and a controlling cylinder having a piston connected to said head and also formed with a by-pass between its opposite ends controlled by a valve actuated through the gas pressure generator.

A further object of the invention is to present a new construction of feeding means

including a shaft and driving drum therefor adapted to be rotated in one direction to tension the drum and to be clutched to the feed shaft when rotated in an opposite direction to actuate said shaft, combined with means for governing the rotation of said shaft controlled by the gas pressure generator.

Other and further objects and advantages of the invention will be hereinafter set forth and the novel features thereof defined by the appended claims.

In the accompanying drawings:

Figure 1 is a vertical section showing the invention applied to a generator;

Figure 2 is a detail vertical section through the by-pass connection and its controlling valves;

Figure 3 is a top plan with portions of the governor broken away;

Figure 4 is a plan of the crank connection at the upper end of the feed shaft; and

Figure 5 is a bottom plan of the cooperating driving drum.

Like reference numerals designate corresponding parts throughout the several figures of the drawings.

In the application of the invention shown, the numeral 10 designates a carbide gas generator which may be of any desired size and construction, this being provided with a feed hopper 11 and a feeding disk 12 suspended by a tubular standard 13 from the top plate 14 of the generator. Extending through the standard 13 is a feed shaft 15 carrying at its lower end beneath the disk 12 oppositely disposed arms 16 between which a chain or other connection 17^a is disposed so as to travel over the material upon the disk and feed a portion thereof to the generator in the rotation of the shaft 15.

The parts so far described may be of any desired construction as the present invention relates to the driving of the feed shaft and governor control therefor.

As comprising an improved means for such driving, the end of the feed shaft above the cover 14 is provided with a disk 17 having a crank pin 18 extending therefrom and connected to a clutch disk 19 which is formed on its upper face with a circumferential series of ratchet teeth 20 which are adapted to cooperate with a clutch pawl 21 carried by the under face of the driving drum 22 rotatably mounted for winding movement upon the disk 19 so as to form in

its opposite movement a one-way clutch to drive the shaft 15 when the drum is rotated in a direction for that purpose. This drum is adapted to be tensioned by any desired means such as a spring or weight, the latter form being shown as comprising a cable 23 secured to the drum and extending over a guide pulley 24 with an actuating weight 25 provided at its lower end. The drum is tensioned by rotating the same through the handle 26 so as to wind the cable thereon, and such movement imparts no power to the drive shaft through the travel of the pawl over the ratchet face, while an opposite movement of the drum through the weight member causes the pawl to engage a ratchet tooth and impart driving motion to the feed shaft.

The control of this feed shaft is effected by an improved construction of governor comprising a cylinder 27 having a piston 28 therein with its rod 29 extended in opposite directions and provided with stops 30 to limit the extent of the piston travel. This cylinder is formed with a by-pass 31 communicating with its opposite ends beyond the limit of piston travel and provided with a cut-off valve 32 adjustable to close the by-pass when the parts are not in operation. The by-pass is also provided with a controlling valve 33 having its stem 34 connected with a diaphragm 35 exposed to the pressure of gas within the generator and normally tensioned downward by a spring 36 to hold said valve in open position until a maximum pressure causes the closing of the same through the flexing of the diaphragm.

The piston rod 29 may be connected with the drive shaft in any desired manner but preferably by means of a slide block 37 operating upon a base 38 and having a pitman 39 pivoted at 40 thereon and connected at its opposite end with the crank pin 18 extending between the plates 17 and 19. This provides a direct connection from the feed shaft to the governor so that the speed of rotation of said shaft will be controlled dependent upon the feed through the by-pass which is graduated by the pressure within the generator, and when this pressure reaches a maximum the by-pass is closed and the feed of carbide ceases.

In the normal operation of the machine the cut-off valve 32 is opened and the control is purely through the pressure valve. The top of the generator may be formed with the usual feed opening 41 closed by a cap 42 clamped in position by a screw 43 mounted in the bracket 44.

The operation of the invention will be apparent from the foregoing description from which it will be seen that the shaft is directly driven from the drum under tension and the speed and continuation of its movement accurately controlled by a simple valve

operating in the by-pass communicating at opposite sides of the piston within the governor cylinder. In the normal operation of the feed shaft the fluid passes from end to end of the governor cylinder so as to balance the operation of the piston therein. When the gas pressure within the generator rises to a predetermined point its action upon the diaphragm tends to close the controlling valve in the by-pass to a greater or less extent and thereby limits the volume of fluid which can pass from end to end of the cylinder. A complete closing of this valve by the pressure within the generator prevents further operation of the piston within the cylinder as it maintains an equal fluid pressure at each side thereof and the operation of the feed is consequently stopped. This provides a simple, efficient and economically constructed means for feeding to a generator the material in the desired and necessary quantities to automatically maintain the pressure of gas necessary to supply the system with which it is connected.

While the specific construction of the invention has been shown and described, it is not confined thereto as changes and alterations may be made without departing from the spirit of the invention as defined by the following claims.

Having thus described my invention, what I claim as new and desire to secure by Letters Patent is:

1. A governor for an acetylene generator comprising a feed shaft, a driving drum operatively connected to said shaft, a cylinder and piston governor connected to said shaft and provided with a by-pass communicating at opposite sides of the piston, and a valve controlling said by-pass and having means adapted for actuation by the gas pressure within the generator.

2. A governor for an acetylene generator comprising a feed shaft, a driving drum operatively connected to said shaft, a cylinder and piston governor connected to said shaft and provided with a by-pass communicating at opposite sides of the piston, a valve controlling said by-pass and having means adapted for actuation by the gas pressure within the generator, and a cut-off valve operating in said by-pass to prevent movement of the parts.

3. A governor for an acetylene generator comprising a feed shaft, a driving drum operatively connected to said shaft, a cylinder and piston governor connected to said shaft and provided with a by-pass communicating at opposite sides of the piston, a controlling valve operating in said by-pass and connected to a diaphragm adapted to be exposed to the gas pressure within the generator, and a spring for normally opening said valve.

4. A governor for an acetylene generator

comprising a feed shaft, a driving drum operatively connected to said shaft, a cylinder and piston governor connected to said shaft and provided with a by-pass communicating at opposite sides of the piston, a valve controlling said by-pass and having means adapted for actuation by the gas pressure within the generator, a piston rod extending from said cylinder, and a pitman 10 connected with said rod and to a crank pin upon the feed shaft.

5. In a generator having a feed shaft, a crank member on said shaft, a governor connection from said member, a clutch disk on 15 said member having a ratchet face a cooperating driving drum having a pawl cooperating with said face, means for tensioning said drum by its rotation in a direction opposite to a driving 20 relation, a governor comprising a cylinder and piston therein having its rod connected to said governor connection and means for controlling the movement of said piston relative to the gas pressure within the generator.

cylinder a piston therein having its rod connected to said cross head, and a conduit connecting the ends of the cylinder and having 25 means actuated by the gas pressure of a generator for controlling the movement of said piston.

6. In a generator having a feed shaft, a crank member on said shaft, a governor connection from said member, a clutch disk on 30 said member having a ratchet face, a driving drum having a pawl cooperating with said face, means for tensioning said drum by its rotation in a direction opposite to a driving 35 relation, a governor comprising a cylinder and piston therein having its rod connected to said governor connection and means for controlling the movement of said piston relative to the gas pressure within the generator.

In testimony whereof I affix my signature.

THOMAS J. SULLIVAN.
